UNITED STATES PATENT OFFICE.

GIOVANNI VENTOLINO, OF BROOKLYN, NEW YORK.

CONSTRUCTION OF REINFORCED-CONCRETE FLOORS, ETC.

Application filed December 19, 1925. Serial No. 76,369.

While adapted to other purposes, my improvements relate more particularly to reinforced concrete floors, so called in the art, in which the concrete surface material is supported and reenforced by basic metallic framework, my object being the attainment of a maximum degree of strength and durability with a minimum quantity of concrete material, and in such manner that rigidity is insured with comparative lightness of structure,—the invention consisting in the specific combination and arrangement of component parts described and claimed, whereby these and other advantages are attained, all as hereinafter fully set forth.

In the accompanying drawings I illustrate a practical embodiment of the essential features of my invention as applied to the construction of a concrete floor, a portion of which is shown in section with the formative means mainly in elevation, although I do not limit myself to the identical structure of parts and appurtenances shown by way of exemplification, since changes may be made in minor details, and equivalent mechanical expedients resorted to with like results, and without departing from the spirit and intent of my invention in this respect.

With this understanding:

Fig. 1 represents a sectional elevation of two adjacent formative truss-units and adjunctive parts, together with superposed concrete;

Fig. 2 is a longitudinal sectional elevation, taken upon plane of line 2—2, Fig. 1, of three truss-units and adjunctive parts in alignment, broken away between successive truss-units;

Fig. 3 represents the portion of concrete floor shown in Figs. 1 and 2, after the removal of the formative supporting means, and illustrating the use of ceiling panels as applied thereto;

Fig. 4 is a section taken upon plane of line 4—4, Fig. 3;

Fig. 5 is a section taken upon plane of line 5—5, Fig. 3;

Fig. 6 is a perspective view of one half of a truss-unit;

Fig. 7 is a perspective view of one of the truss-units;

Fig. 8 is a perspective view of a portion of one of the floor matrix plates;

Fig. 9 is a perspective view of one of the longitudinal connective spacing rods, broken away medially;

Fig. 10 is a detail view of connection between superposed parts of matrix plates.

The object of my invention being, primarily, the formation of a continuous integral concrete structure C, having parallel trapezoidal portions C', which function as joists to the intervening portions thereof, as will be understood by reference more particularly to Fig. 3, of the drawings, I herein set forth the means and method employed in the attainment of a floor and ceiling construction, with the understanding that essentially the same means and method may be utilized in the formation of a wall or analogous partition of a building or enclosure.

To this end I first position a parallel series of twin supporting girders or beams B, at the requisite distance apart to afford space for the truss-units T, to be used in the formation of the superstructure as illustrated in the first two figures of the drawings.

Each truss-unit T, one of which is shown in perspective in Fig. 7, of the drawings, consists of twin brace sections T', T', one of which is shown in perspective detail in Fig. 6. Each brace section T', consists of a metallic base plate t, to which is rigidly secured an upright member t', formed with a lateral extension t², the other extremity of which is rigidly connected with the base plate t, by means of a diagonal brace t³. The opposed upper portions of the upright members t', t', of the brace sections T', T', are inclined and curved inward as related to each other in the making of a truss-unit T, the ends of said lateral extensions t², t², overlapping to constitute the top of the arch of the truss-unit T.

The base plates t, t, are of sufficient length to overlap centrally as incorporated in the truss-unit T, and are formed with coincident holes t⁴, t⁴, for the accommodation of bolts a, a, provided with nuts a', a', by means of which the two base plates t, t, of a truss-unit T, are rigidly attached. The lateral extensions t², t², are also formed with coincident slots t⁵, t⁵, for the accommodation of the shouldered ends of the spacing bars s, s, which are interposed between the truss-

units T, as shown more particularly in Fig. 2, of the drawings.

The base plates t, t , of the twin sections T', T', protrude sufficiently beyond the upper end members t', t' , thereof, to admit of insertion between the superposed beams B, B, as shown in Fig. 1, of the drawings, thereby affording adequate support for each truss-unit T.

- 10 When the truss-units T, are thus positioned upon and between adjacent rows of parallel twin supporting beams B, matrix plates M, are laid upon and between adjoining truss-units T, and over the spacing bars s, s, said matrix plates M, being of sufficient length for the purpose, and two being provided for each span,—one for each side of the arch thus formed, said plates M, overlapping each other centrally so as to cover 15 and enclose the truss-units and the spaces therebetween, the lower edges m, of said matrix plates M, being interposed between the truss end members t', t', and the supporting beams B, B, and said lower edges 20 25 m, m, resting upon the base plates t, t, of the truss-units and against the adjacent sides of the beams B, B, as shown more particularly in Fig. 1, of the drawings.

Adjacent to said lower edges m, of the matrix plates M, they are formed with externally protuberant longitudinal ribs m', m', which not only constitute shoulders for resting against the upper beams B, but also function as means whereby grooves c, c, are 30 35 created in the joist-like portions C', of the cast attained by filling the moulding space above the matrix plates M, with concrete. These grooves c, c, afford support for the ceiling panels p, between the joist portions

C', of the cast as indicated in Fig. 3, of the drawings.

Metallic reenforcing and binding wires r, are imbedded in the concrete filling of the mould space above and between the matrix plates M.

The overlapping edges of the matrix plates are formed with perforations m², for the accommodation of wire binders m³, as shown in Fig. 10, of the drawings.

What I claim as my invention and desire 50 to secure by Letters Patent, is:—

1. A truss-unit of the character described comprising twin brace sections each consisting of a base member and an angular member having one end secured to the base member, the two sections being relatively arranged with their base members overlapped and secured together, and portions of the angular members overlapped and secured to each other, and diagonal braces disposed 55 60 with their ends secured to the base member and to the overlapped portions of the angular members.

2. A truss-unit of the character described comprising twin brace sections each consisting of a base member and an angular member having one end secured to the base member, the two sections being relatively arranged with their base members overlapped and secured together, and portions of the 65 70 angular members overlapped and secured to each other, and diagonal braces disposed with their ends secured to the base members and to the overlapped portions of the angular members, said braces being crossed at 75 substantially their centres.

GIOVANNI VENTOLINO.
